UNITED STATES PATENT OFFICE.

FRANK ANSTETT, OF WILKES-BARRE, PENNSYLVANIA.

SAXOPHONE.

Application filed February 24, 1923. Serial No. 620,917.

To all whom it may concern:

Be it known that I, FRANK ANSTETT, a citizen of the United States, residing at Wilkes-Barre, in the county of Luzerne and State of Pennsylvania, have invented certain new and useful Improvements in Saxophones, of which the following is a specification.

This invention relates to saxophones; and it consists in certain improvements to the key mechanism for producing the tones of B flat and C natural in the middle register, and for producing the upper tones D, E flat, E and F, as hereinafter fully described and claimed.

In the drawings, Figure 1 is a rear side view of a portion of a tenor saxophone, showing the C natural and B flat keys of the middle register, constructed according to this invention, and looking in the direction of the arrow 13 in Fig. 2. Fig. 2 is a cross-section through the body of the instrument, taken on the line 2-2 in Fig. 1. Fig. 3 is a side view of the parts shown in Fig. 1, looking in the direction of the arrows 14 in Figs. 1 and 2. Fig. 4 is a cross-section through the body, taken on the line 4-4 in Fig. 1. Fig. 5 is a front view of the upper part of the instrument showing the keys for the high notes D, E flat, E and F. Fig. 6 is a side view of the parts shown in Fig. 5, looking in the direction of the arrow 6 in Fig. 5. Figs. 7, 8 and 9 are cross-sections, taken on the lines 7-7, 8-8, and 9-9, respectively in Fig. 5. Fig. 10 is a detail view of the spindle 75 and the parts mounted on it. Fig. 11 is a detail view of the spindle 86 and the parts mounted on it. Fig. 12 is a rear view of the spindle 46 and the parts mounted on it. Fig. 13 is an end view of the lever 100.

In the Figs. 1, 3, 5 and 6 many keys and other parts, belonging to the instrument as ordinarily constructed, have been omitted for clearness, and as they are not parts of the present invention.

The saxophone illustrated is a tenor saxophone in B flat of approved construction, provided with a conical body portion 15. The body portion has the usual button 16 on which the thumb of the left hand usually rests, and which is located on the rear side of the body portion, next to the body of the player. According to the present invention

the ball of the thumb does not rest directly 55 on the button 16 but on the thumb plate 17 of an additional key 18 which projects crosswise of the body and is pivoted on a longitudinal spindle 19. The thumb plate 17 is normally pressed down on the button 60 16 by the thumb, and the usual octave key (not shown) is operated by the tip of the thumb in the usual manner.

The B flat and C natural tones are produced on this instrument by the usual keys 65 (not shown), and this instrument is provided at its rear side with the usual auxiliary B flat pad 20 and C natural pad 21 for use with a different and approved fingering. These two pads 20 and 21 are however operated in a novel manner according to this invention. The B flat pad 20 is mounted on a pivoted key 22 provided with a spring 23 for opening it, and having an extension 24 on the other side of its pivot 70 from the pad 20. When the third finger of the left hand is pressing down the ordinary G key of the instrument, (not shown), the B flat pad 20 is closed by an arm 25 (partially shown) which comes under the extension 24, and which arm is not a part of the present invention.

The C natural pad 21 is mounted on a pivoted key 26 provided with a spring 27 for opening it, and having an extension 28 85 on the other side of its pivot from the pad 21. When the second finger of the left hand is pressing down the ordinary A key of the instrument (not shown), the C pad 21 is closed by an arm 29 (partially shown) 90 which comes under the extension 28, and which arm is not a part of the present invention.

According to this invention the B flat pad 20 and the C pad 21 are normally closed 95 by the thumb key 18. A spindle 30 is mounted in bearings 31 on the body portion 15, and is arranged longitudinally thereof, and parallel to the keys 22 and 26. This spindle is operated by an arm 32 secured 100 on it, and provided with a lug 33 which comes over the end portion of the key 18 on the other side of its pivot from the thumb plate 17.

Two arms 34 and 35 are secured on the 105 spindle 30 for operating the keys 22 and 26. The arm 34 has a head 36 provided with a slot 37, and the key 22 has a standard

38 which projects upwardly from it at its pivot. A spring 39 is secured at one end in the standard 38, and its free end portion engages with the slot 37. A guard 40, channel-shaped in cross-section, is secured to the standard 38, and extends longitudinally over the spring 39, to protect it from injury. The B flat pad is closed by the thumb key 18 by the downward pressure of the upper end of the slot 37 on the free end portion of the spring 39.

The means for closing the C pad are similar to those for closing the B flat pad. The arm 35 has a head 41 provided with a slot 42, and the key 26 has a standard 43. A spring 44 is secured to the standard 43, and its free end portion engages with the slot 42. A guard 45 is secured to the standard 43, and protects the spring 44 from injury.

In order to raise the B flat and C natural pads 20 and 21 with facility in playing certain passages, and to avoid cross-fingering with the fingers of the left hand, keys are provided for raising the B flat and C natural pads with the right hand, at the larger part of the body portion 15. A spindle 46 is arranged longitudinally of the instrument, and is mounted in bearings 47. A sleeve 48 is mounted to rock on the spindle 46, and an arm 49 is secured to it with its end projecting crosswise over the end portion of the extension 24 of the B flat key 22. A finger piece 50 is secured to a short sleeve 51 also mounted on the spindle 46, and the sleeve 51 is connected to the sleeve 48 by a crank bar 52. When the finger piece 50 is depressed by the first finger of the right hand the arm 49 trips open the B flat key 22.

An arm 53 is secured on a sleeve 48' mounted to rock on the spindle 46, and its free end portion projects crosswise over the extension 28 of the C natural key 26. A finger piece 54 is secured to a short sleeve 51' also mounted on the spindle 46, and the sleeves 48' and 51' are connected by a crank bar 52', as shown in Fig. 12. When this finger piece 54 is depressed by the first finger of the right hand the arm 53 trips open the C natural key 26.

The finger of the right hand overcomes the pressure of the springs 39 and 44 in thus operating the B flat and C natural keys. The slots 37 and 42 in the heads 36 and 41 are provided to permit the free end portions of the springs 39 and 44 to move downwardly when the thumb is off the thumb plate 17, and the B flat key 20 and the C natural key 21 are closed by the fingers of the left hand in the usual manner operating the arms 25 and 29.

The shank of the finger piece 54 overlaps the crank bar 52, and when the finger piece 54 is depressed to open the C natural

key it operates the crank bar and also opens the B flat key, venting the instrument freely at this point, and thereby improving the C natural tone in quality.

The smaller portion of the body of the instrument is provided on its front side with pads 60, 61 and 62 for the B natural, C natural and C sharp tones, which are operated by key mechanism of approved construction, and as ordinarily used and operated by the first and second fingers of the left hand. The pads 63 for the D tone, 64 for the E flat tone, 65 for the E natural tone, and 66 for the F tone are all arranged in their usual positions, and all have springs which normally hold them closed, but they are operated by novel key mechanism according to this invention.

The D pad 63 is mounted on one end of a key 67 having a pivot 68 at its other end. A spindle 69 is journaled in bearings 70, and is arranged parallel to the key 67. A finger piece 71 projects laterally in one direction from the spindle 69, and is curved around the body and arranged with its free end a little farther towards the large end of the body than the B pad 60. A trip arm 72 projects laterally from the spindle 69 under the middle part of the D key 67. The D pad 63 is raised by depressing the finger piece 71.

The E flat pad 64 is mounted on one end of a key 73 having a pivot 74 at its other end. A spindle 75 is pivoted on the pointed end portions of two screws 75' mounted in bearings 76, and is arranged parallel to the key 73. A finger piece 76' projects laterally in one direction from the spindle 75, and is curved around the body and arranged between the B and C pads 60 and 61. A trip arm 77 projects laterally from the spindle 75 under the middle part of the key 73, and the E flat pad 64 is raised by depressing the finger piece 76'.

The E natural pad 65 is mounted on one end of a key 78, the middle part of which is mounted on a pivot 79. A sleeve 80 is mounted on the middle part of the spindle 75, and a short sleeve 81 is also mounted on the spindle 75 opposite the other end of the E natural key 78 from the pad. These two sleeves 80 and 81 are rigidly connected together by a crank bar 82, and this crank bar has an extension 82' at one end which projects under a lug 83 on the finger piece 76' of the E flat key. An arm 84 is secured on the sleeve 80, and projects on the other side of it from the crank bar 82. A lever 85 is provided for depressing the arm 84, and one end of this lever is pivoted loosely on a spindle 86 which is mounted to rock in bearings 87 on the body of the instrument. The lever 85 has a finger piece 88 which projects at a right angle from its free end portion, which is ar-

ranged over the crank bar 82. The short sleeve 81 has an arm 89 secured to it, and this arm overlaps the end portion of the E natural key 78, on the other side of its pivot 6 from its pad 65. When the finger piece 88 is depressed, the lever 85 depresses the arm 84, and raises the crank bar 82, which in turn depresses the arm 89, and raises the E natural pad 65.

10 The E flat pad is raised by the finger piece 88 simultaneously with the E natural pad, by means of the extension 82' on the crank bar 82, which extension raises the lug 83 on the finger piece 76' of the E flat key.

15 The raising of the E flat pad vents the instrument freely at this point, and thereby clarifies the E natural tone.

The high F pad 66 is mounted on one end of a key 90, which has a pivot 91 at its 20 other end. The spindle 75 has a sleeve 92 mounted loosely on it, and this sleeve has a trip arm 93 secured to it and projecting under the middle part of the key 90. A sleeve 94 is also mounted loosely on the spindle 75, and the two sleeves 92 and 94 are rigidly connected together by a crank bar 95 which extends longitudinally of the spindle 75, at one side of the sleeve 81. The sleeve 94 has an arm 96 secured on it, which 30 projects from it laterally in one direction, and which is arranged adjacent to the arm 84. This arm 96 has an extension 97 which projects in the opposite direction from its main portion, under the crank bar 82, and 35 which engages with the crank bar 82 and raises it when the arm 96 is depressed. A lever 98 is provided for depressing the arm 96, and one end of this lever is secured on the spindle 86. The lever 98 is arranged 40 parallel to the lever 85, and it has a finger piece 99 at its free end which projects from it at a right angle, and which overlaps a portion of the finger piece 88 which operates the E natural key. These two finger pieces 45 99 and 88 are arranged so that a finger can slide easily off the finger piece 99 onto the finger piece 88, to permit the finger piece 99 to rise without permitting the finger piece 88 to rise.

50 When the finger piece 99 is depressed, the lever 98 depresses the arm 96, and operates the crank bar 95 and trip arm 93 so as to raise the high F pad. The E natural and E flat pads are raised simultaneously 55 with the F pad by the downward pressure of the finger piece 99 on the finger piece 88, and also by the action of the crank bar 82 which is raised when the lever 98 depresses the arm 96 and raises its extension 97.

60 The raising of the E natural and E flat pads simultaneously with the high F pad operates to improve the high F tone.

In order to operate the high F key with the right hand, which is a great convenience 65 in certain passages of music, the spindle

86 is extended longitudinally to the larger end portion of the instrument, and a lever 100 is secured on it and provided with a finger plate 101. The lever 100 curves around the body of the instrument in the 70 same direction as the finger pieces 88 and 99, and its finger plate 101 is preferably arranged between the tone holes of the lower E and F keys of the instrument as ordinarily constructed, and which keys are 75 not shown, as they do not form a part of this invention. When the finger plate 101 is depressed it also depresses the finger piece 99, as both of them are secured on the same spindle 86, so that the high F pad is 80 raised and with it the E natural and E flat pads as hereinbefore described.

What I claim is:

1. In a saxophone, a pivoted tone key provided with an opening spring, a key pivoted crosswise of the pivot of the said tone key and having a plate for the thumb of the left hand, and means operatively connecting the two keys, said means being provided with a closing spring which operates to depress the tone key and overcome the pressure of its opening spring when the thumb key is depressed.

2. In a saxophone, a pivoted tone key provided with an opening spring, a closing spring secured at one end to the said tone key and arranged longitudinally of it, a pivoted key having a plate for the thumb of the left hand, and means operatively connecting the thumb key with the free end portion of the said closing spring so that the tone key is closed when the thumb key is depressed.

3. In a saxophone, a pivoted tone key provided with an opening spring, a closing 105 spring secured at one end to the said tone key, a pivoted key provided with a plate for the thumb of the left hand on one side of its pivot, a pivoted spindle arranged parallel to the said tone key, an arm secured on 110 the said spindle and engaging with the thumb key on the other side of its pivot from its thumb plate, and a closing arm secured on the said spindle and engaging with the free end portion of the said closing 115 spring and operating to close the tone key when the thumb plate is depressed.

4. In a saxophone, a pivoted tone key provided with means for closing it as set forth in claim 3, the closing arm of the said 120 means being provided with a slot which engages with the free end portion of the closing spring, thereby permitting the tone key to be closed independently of the thumb key and when the thumb key is not 125 depressed.

5. In a saxophone, a pivoted tone key provided with means for closing it as set forth in claim 3, said tone key being provided with an upwardly projecting standard, the 130

closing spring of the said means being secured at one end to the said standard, and the said standard having a guard secured to it and projecting longitudinally over the 5 said closing spring.

6. In a saxophone, a pivoted C natural key, and a pivoted B flat key, each provided with an opening spring, a key pivoted adjacent to the said C key and having a 10 plate for the thumb of the left hand, and means which operatively connect the thumb key with the said C and B flat keys, said means being provided with two closing springs which operate to depress the respective C and B flat keys simultaneously when the thumb plate is depressed.

7. In a saxophone, a pivoted tone key provided with an opening spring and a pad for closing a tone hole, a closing spring secured 20 at one end to the said key, a pivoted key provided with a plate for the thumb of the left hand on one side of its pivot, a pivoted spindle arranged longitudinally of the body of the instrument, an arm secured to the 25 said spindle and engaging with the thumb key on the other side of its pivot from its thumb plate, and a closing arm secured on the said spindle and engaging with the free end portion of the said closing spring and 30 operating to depress the tone key to close the tone hole when the thumb plate is depressed.

8. In a saxophone, the combination with the parts set forth in claim 2, of a pivoted 35 key operated by the right hand and provided with an arm which projects crosswise of the tone key and which affords a means for raising it when the thumb key is depressed.

40 9. In a saxophone, the combination, with the parts set forth in claim 2, of a spindle arranged longitudinally of the instrument, a sleeve mounted loosely on the said spindle, an arm secured on one end portion of the 45 said sleeve and arranged crosswise of the said tone key and affording a means for raising it when the thumb key is depressed, and a finger piece secured on the other end portion of the sleeve and adapted to be 50 operated by the right hand.

10. In a saxophone, the combination, with the parts set forth in claim 6, of two pivoted keys operated by the right hand and provided with arms which project cross- 55 wise of the C key and the B flat key and which afford a means for raising each of them when the thumb key is depressed.

11. In a saxophone, the combination with the parts set forth in claim 6, of a spindle 60 arranged longitudinally of the instrument, sleeves arranged in pairs and mounted on the said spindle, crank bars connecting the two sleeves of each pair, arms secured to one sleeve of each pair and projecting crosswise 65 of the said C and B flat keys and operating

to raise them, and finger pieces secured to the other sleeve of each pair and adapted to be operated by the right hand.

12. In a saxophone, a key pivoted at one end and having a pad for closing a tone 70 hole at its other end, a spring normally closing the said key, a spindle pivoted parallel to the said key, a finger piece secured to one end portion of the spindle, and a trip arm secured to the other end portion of the spindle 75 and projecting under the middle part of the said key and operating to open the key when the said finger piece is depressed.

13. In a saxophone, a key pivoted at one end and having a pad for the high E flat 80 tone at its other end, a spring normally closing the said key, a spindle pivoted parallel to the said key, a finger piece secured to one end portion of the spindle and projecting laterally in one direction, and an 85 opening arm secured on the other end portion of the said spindle and projecting laterally under the middle part of the said key in the other direction and operating to open the key when the said finger piece is depressed. 90

14. In a saxophone, a key pivoted at its middle part and having a pad for high E tone at one end, a spring normally closing 95 the said key, a spindle arranged parallel to the said key, two sleeves mounted loosely on the said spindle, a crank bar connecting the two sleeves, an opening trip arm secured to one sleeve and projecting over the other end portion of the said key, an opening arm 100 secured to the other sleeve and projecting on the same side of the spindle as the said trip arm, and a lever arranged crosswise of the said spindle and pivoted at one end and having a finger piece at its free end, the middle part of the said lever being arranged to bear on the free end portion of the said opening arm, said lever operating to depress the two said arms and open the said key when the said finger lever is depressed. 105

15. In a saxophone, a high E tone key provided with opening mechanism as set forth in claim 14, the crank bar of the said opening mechanism being provided with means for opening the E flat key simultaneously with the opening of the said high E key. 115

16. In a saxophone, a key pivoted at one end and having a pad for the high F tone at its other end, a spring normally closing 120 the said key, a spindle arranged parallel to the said key, two sleeves mounted loosely on the said spindle, a crank bar connecting the two sleeves, an opening trip arm secured to one sleeve and projecting under the middle 125 part of the said key, an opening arm secured to the other sleeve and projecting on the other side of the spindle from the said trip arm, and an opening lever arranged crosswise of the said spindle and 130

pivoted at one end and having a finger piece at its free end, the middle part of the said lever being arranged to bear on the free end portion of the said opening arm, 5 said lever operating to depress the two said arms and open the said key when the said finger lever is depressed.

17. In a saxophone, a high F tone key provided with opening mechanism as set forth in claim 16, the opening arm of the 10 said mechanism being provided with means arranged on the other side of its pivot from its main portion for opening the high E key simultaneously with the opening of the 15 said high F key.

18. In a saxophone, a high F tone key provided with opening mechanism as set forth in claim 16, the said mechanism being provided with means for opening the high 20 E and the high E flat keys simultaneously with the opening of the said high F key.

19. In a saxophone, pivoted keys for the high E flat, high E and high F tones, springs normally closing the said keys, a 25 pivoted spindle arranged longitudinally of the instrument, sleeves arranged in pairs and mounted loosely on the said spindle, crank bars connecting the two sleeves of each pair, trip arms secured to one sleeve of each pair and engaging with the said high 30 E and high F keys, opening arms secured to the other sleeve of each pair and operating to open the said high E and high F keys when depressed, pivoted levers arranged crosswise of the said pivoted spindle and 35 provided with finger pieces and operating to depress the said opening arms when said finger pieces are depressed, and a trip arm and a finger piece secured directly to the said pivoted spindle and operating to open 40 the said high E flat key when the said finger piece is depressed.

20. In a saxophone, the combination with a high F key provided with means for opening it as set forth in claim 16, of a 45 pivoted spindle arranged longitudinally of and extending to the larger end portion of the instrument and having the opening lever of the said means secured on one end portion of it, and a finger piece secured on 50 the other end portion of the said spindle and operating to open the high F key when depressed with the right hand.

In testimony whereof I have affixed my signature.

FRANK ANSTETT.
